UNITED STATES PATENT OFFICE.

JOHN HOLLAND LETZ, OF CROWN POINT, INDIANA, ASSIGNOR TO THE LETZ MANUFACTURING COMPANY, OF CROWN POINT, INDIANA, A CORPORATION OF INDIANA.

GRINDING-BUR.

1,244,514.

Specification of Letters Patent. Patented Oct. 30, 1917.

Application filed January 17, 1917. Serial No. 142,801.

To all whom it may concern:

Be it known that I, JOHN HOLLAND LETZ, a citizen of the United States, and a resident of Crown Point, in the county of Lake and 5 State of Indiana, have invented certain new and useful Improvements in Grinding-Burs, of which the following is a full, clear, and exact specification.

My invention is concerned with grinding 10 burs of the type shown in the Letz Patent No. 437,699, and is designed to produce a dress of the bur that will grind more rapidly and economically than can be done with the dress shown in the aforesaid patent.

15 To illustrate my invention, I annex here-to a sheet of drawings, in which the same reference characters are used to designate identical parts in all the figures, of which,—

Figure 1 is a view of the grinding face 20 of a bur embodying my invention;

Fig. 2 is a section on the line 2—2 of Fig. 1; and

Fig. 3 is an enlarged view of a portion of the face of the bur shown in Fig. 1.

25 The body of the bur preferably consists of a thin annular casting, which may be reinforced on its back by employing one or more annular ribs *v*. Its grinding surface is generally flat, except so far as it is broken 30 by the grinding ribs to be described, which, it will be understood, are preferably cast integral with the body and ground off on a flat stone so as to form cutting edges and grinding surfaces on all the ribs in the same plane, 35 and adapted to coöperate with similar ridges and surfaces similarly formed on the similar ribs on the opposed face of the companion bur.

The ribs are preferably arranged in 40 groups, substantially triangular in their general outline, and preferably six in number. The ribs going to make up each of the six groups have preferably the same design, or substantially so, so that the description of 45 one group will suffice for all of them.

Considering an imaginary radial line, such as a central vertical line in Fig. 1 or 50 3, as the base line for the purposes of description, the main ribs *a*, *b*, *c*, *d*, *e* and *f* are parallel to each other and all extend at an angle of substantially sixty degrees to the base line. These ribs are preferably interrupted at intervals, and thus consist of sections *a*, *a'*, *a''*, *a'''*, *a''''*, *b*, *b'*, *b''*, *b''''*, *c*, *c'*,

c'', *c'''*, *c''''*, *d*, *d'*, *d''*, *d''''*, *e*, *e'*, *e''* and *f*. The 55 baffle ribs, *g*, *h*, *j*, *k*, *l*, *m*, *n*, *o*, *p*, *q*, *r*, *s*, *t*, between the main ribs extend at right angles thereto, and are preferably connected to the ends of the main-rib sections, each of said sections having one baffle-rib section attached 60 to each end but extending in opposite directions therefrom. These baffle-rib sections, as will be seen, are *g*, *g'*, *h*, *h'*, *h''*, *j*, *j'*, *j''*, *k*, *k'*, *k''*, *k''''*, *l*, *l'*, *l''*, *l''''*, *m*, *m'*, *m''*, *m''''*, *n*, *n'*, *n''*, *n''''*, *o*, *o'*, *o''*, *p*, *p'*, *p''*, *q*, *q'*, *r*, *r'*, *s* and *t*. 65 The baffle ribs connected to the lower ends of the main-rib sections thus form with the next main-rib sections toward the center an angle with an opening at its apex and its sides converging in the direction of movement of the grain. The ribs are preferably designed so as to leave the plane triangular spaces *w* between each group.

In operation, the main-rib sections of one 70 bur coöperate with half of the baffle-rib sections of the companion bur to shear the grain between their cutting edges in a manner that will be readily understood by those conversant with the use of these burs. The converging ribs forming the angles before 75 described force the grain as it tends to move radially outward into the angles which force it upwardly from the faces of the burs so as to bring it into the shearing planes of the burs, so that before it reaches the peripheries of the burs all of it will be sheared and crushed. The half of the baffle ribs that do not have any material shearing action assist in forcing the grain into the above- 80 mentioned angles and prevent its moving 85 outwardly directly along the line of the main ribs.

What I claim as new, and desire to secure by Letters Patent of the United States, is:

1. A grinding bur consisting of a generally flat disk having a series of grinding ribs projecting therefrom and having their flat top surfaces in the same plane and forming shearing edges, said ribs being arranged in plural groups consisting of the main 90 parallel ribs extending at generally acute angles to radial lines, and short baffle ribs at substantially right angles to the main portions, both sets of ribs combining to form comparatively wide, tortuous passages to 95 the periphery generally parallel to the line of the main ribs, and very contracted more direct passages for the finely ground grain 100 105

on substantially radial lines, some of the baffle ribs serving to direct the finely ground grain to the more direct passages.

2. A grinding bur consisting of a generally flat disk having a series of grinding ribs projecting therefrom and having their flat top surfaces in the same plane and forming shearing edges, said ribs being arranged in plural groups consisting of the 10 main parallel ribs extending at generally acute angles to radial lines, and short baffle ribs at substantially right angles to the main portions, said baffle ribs being connected to the main ribs, one at each end and extending

therefrom in opposite directions, both sets 15 of ribs combining to form comparatively wide, tortuous passages to the periphery generally parallel to the line of the main ribs, and very contracted more direct passages for the finely ground grain on substantially radial lines.

In witness whereof, I have hereunto set my hand and affixed my seal, this 16th day of December, A. D. 1916.

JOHN HOLLAND LETZ. [L. S.]
